Attorneys.

UNITED STATES PATENT OFFICE.

EUGENE COLBERT BRYAN, OF KISSIMMEE, FLORIDA.

FRUIT CONTAINER.

Application filed December 24, 1921. Serial No. 524,651.

To all whom it may concern:

Be it known that I, EUGENE COLBERT BRYAN, a citizen of the United States, residing at Kissimmee, in the county of Osceola 5 and State of Florida, have invented certain new and useful Improvements in Fruit Containers; and I do hereby declare the following to be a full, clear, and exact description of the invention, such as will enable 10 others skilled in the art to which it appertains to make and use the same.

My present invention relates to improvements in fruit containers, and it is intended to provide a container for grapefruit or 15 other fruit in which the fruit will be protected against being bruised or injured in any way, and may be properly ventilated and may be inspected as to condition, preservation or the like without tampering with the 20 package; and in which the package may be effectually sealed and kept sealed until it is desired to open same at the place of delivery.

My invention is especially intended to 25 provide a cheap, simple and efficient container which may be used in shipping fruit in small packages by parcel post, or express, and which packages may be made cheap enough to be thrown away after the 30 same have been delivered, or may be returned for further use if desired.

My present invention relates more especially to an improvement on or modification of the arrangement shown in my earlier 35 application filed October 12, 1921, Ser. No. 507193, and entitled Improvements in fruit container.

My invention will be more fully understood after reference to the accompanying 40 drawings, in which like parts are indicated by similar reference symbols throughout the several views, and in which:—

Figure 1 is a plan view of the blank which constitutes the container body when laid 45 down in a flat condition.

Figure 2 is a perspective view of the set-up container.

Figure 3 shows a section along the longitudinal axis of the container; and

Figure 4 is a detail view showing one of the fastening plates detached.

A represents the container body which is shown in Figure 1 in the form of a flat blank which may be made of wood veneer, 50 cardboard, stiff leather, or any other suitable light and flexible material, which blank

is provided near its opposite ends with perforations *a* and *a'* adapted to receive fastening wires or strings. Since strings or cords made of textile material are apt to 60 stretch and get loose, I prefer to use as a fastening means light metal wire, as will be hereinafter more fully described.

B and *B'* represent two disks preferably made of wood or cardboard, or other light 65 material sufficiently rigid to give the requisite stiffness to the package when the parts are in the assembled relation.

D and *D'* represent two fastening plates to which the loops of the longitudinal fastening wires are adapted to be connected. 70 These plates are preferably made of thin resilient metal, and have oppositely disposed clips or prongs *d* and *d'* stamped out thereof. These prongs are preferably cut 75 away at their bases, as at *d*^o, not only to facilitate the springing of the prong outward, but also to afford notches to engage the fastening wire.

The fastening wires for holding in the 80 heads comprise two double loops *E* and *E'* which are symmetrically arranged on opposite sides of the container which the parts are in the assembled relation. Each loop has one of its ends as *e* fastened to the 85 prong of the corresponding plate, and the free end *e'* is then rove through the perforations *a* and *a'*, and back again through the adjacent perforations, and is secured to the same prong as the end *e*. 90

The other wire *E'* has its ends preferably fastened to the opposite prong *d'* of the same plate *D* in a similar way, and its loop is adapted to engage the prong *d'* of the plate *D'*, so that when the two wire loops 95 and the corresponding fastening plates and heads are in the assembled relation, as shown in Figs. 2 and 3, the fastening plates hold the wires taut and hold the heads in place against outward displacement. The 100 contents of the package take care of any inner movement of the heads.

As a further fastening means I attach one or more circumferential wires *F*, having their ends twisted together, as at *f*, which 105 tightly engage the package circumferentially and prevent the body portion from being extended outwardly. These circumferential wires add stiffness and strength to the package. 110

In assembling the parts, the body member or circumferential shell of the package is

shaped around the disks B and B', preferably leaving an opening between the adjacent edges of the body portion, as shown at G, through which the fruit H, or other contents of the package, may be seen when the package is sealed, but without breaking the package. The circumferential binding, such as F, is then applied. The loops E and E' and the corresponding plates may be previously attached to the body portion, or may be subsequently attached, as desired.

For purposes of filling, one of the heads may be taken out and the package filled, the missing head is then inserted and the corresponding fastening plate put in place, and the loop of the opposite longitudinal wire slipped over the free prong of the said plate, thus effectually holding both heads in place and closing the package.

If desired a seal, indicated in dotted lines at I, may be attached to the heads so that the package can not be surreptitiously opened without the fact being known.

In order to open the package, break the seal and pry out the wire loop from the corresponding prong of one of the fastening plates, remove said plate and slip out the adjacent head and one end of the package will be completely opened. It will be seen that the parts may be replaced as before and the package used over again in the assembled relation, or the package may be knocked down and re-shipped for further use.

It will be obvious that various modifications might be made in the herein described construction and in the combination and arrangement of parts which could be used without departing from the spirit of my invention; and I do not mean to limit the invention to such details except as particularly pointed out in the claims.

In the claims I have used the term "wires" for brevity, meaning thereby any flexible fastening means such as steel or brass wire, cord or string of any kind, which is suitable for the purpose of providing a flexible fastening means to engage the exterior of the container and to hold the same against lateral expansion and also to hold the heads in place.

Having thus described my invention what I claim and desire to secure by Letters Patent of the United States is:

1. A container comprising a body member in the form of a blank adapted to be rolled into substantially cylindrical form, said body portion being perforated to permit the insertion of a fastening wire or string, stiffening heads in the form of circular disks enclosed in said body member near the ends thereof, wires rove through said holes and forming double loops extending axially of said container and on the exterior thereof, and fastening plates having oppositely dis-

posed resilient clips stamped therefrom, said clips being adapted to engage the loops in said wires, substantially as described.

2. A container comprising a body member in the form of a blank adapted to be rolled into substantially cylindrical form, said body portion being perforated to permit the insertion of a fastening wire or string, stiffening heads in the form of circular disks enclosed in said body member near the ends thereof, wires rove through said holes and forming double loops extending axially of said container and on the exterior thereof, and fastening plates having oppositely disposed resilient clips stamped therefrom, said clips being adapted to engage the loops in said wires, with wires secured circumferentially over said container, and holding the body member against expansion laterally, substantially as described.

3. A container comprising a body member in the form of a blank adapted to be rolled into substantially cylindrical form, said body portion being perforated to permit the insertion of a fastening wire or string, wires rove through said holes and forming double loops extending axially of said container and on the exterior thereof, and fastening plates having oppositely disposed resilient clips stamped therefrom, said clips being adapted to engage the loops in said wires, substantially as described.

4. A container comprising a body member in the form of a blank adapted to be rolled into substantially cylindrical form, said body portion being perforated to permit the insertion of a fastening wire or string, wires rove through said holes and forming double loops extending axially of said container and on the exterior thereof, and fastening plates having oppositely disposed resilient clips stamped therefrom, said clips being adapted to engage the loops in said wires, with wires secured circumferentially over said container, and holding the body member against expansion laterally, substantially as described.

5. A container comprising a body member in the form of a blank adapted to be rolled into substantially cylindrical form, said body portion being perforated to permit the insertion of a fastening wire or string, stiffening heads in the form of circular disks enclosed in said body member near the ends thereof, wires rove through said holes and forming double loops extending axially of said container and on the exterior thereof, and fastening plates made of resilient metal adapted to lie flat against the exterior of said heads, said plates having oppositely disposed resilient clips or prongs stamped therefrom, said clips being adapted to engage the loops in said wires, with wires secured circumferentially over said container, and holding the body mem-

ber against expansion laterally, substantially as described.

6. A container comprising a body member in the form of a blank adapted to be 5 rolled into substantially cylindrical form, said body portion being perforated to permit the insertion of a fastening wire or string, stiffening heads in the form of circular disks enclosed in said body member 10 near the ends thereof, wires rove through said holes and forming double loops extending axially of said container and on the exterior thereof, and means for detachably connecting the adjacent loops at each end 15 of the package, substantially as described.

7. A container comprising a body member

in the form of a blank adapted to be rolled into substantially cylindrical form, said body portion being perforated to permit the insertion of a fastening wire or string, 20 stiffening heads in the form of circular disks enclosed in said body member near the ends thereof, wires rove through said holes and forming double loops extending axially of said container and on the exterior thereof, 25 and means for detachably connecting the adjacent loops at each end of the package, with wires secured circumferentially over said container, and holding the body member against expansion laterally, substantially 30 as described.

EUGENE COLBERT BRYAN.
